(57) **CLAIM**

I claim the ornamental design for a handle, as shown and described.

DESCRIPTION

FIG. 1 is a front perspective view of a handle from above, showing my design;

FIG. 2 is a rear perspective view of the handle from beneath; FIG. 3 is a right side elevational view of the handle, the left side elevational view being a mirror image;

FIG. 4 is a top plan view of the handle;

FIG. 5 is a bottom plan view of the handle;

FIG. 6 is a front elevational view of the handle; and,

FIG. 7 is a rear elevational view of the handle.

The broken line drawing of the bolt, buts, and washers is for illustrative purposes only and forms no part of the claimed design.
